UNITED STATES PATENT OFFICE.

GEORGE WORTH, OF NEW YORK, N. Y.

WINDOW.

SPECIFICATION forming part of Letters Patent No. 660,285, dated October 23, 1900.

Application filed December 7, 1899. Serial No. 739,478. (No model.)

To all whom it may concern:

Be it known that I, GEORGE WORTH, a citizen of the United States, residing at New York, (Brooklyn,) in the county of Kings and State 5 of New York, have invented certain new and useful Improvements in Windows, of which the following is a full and complete specification, such as will enable those skilled in the art to which it appertains to make and use 10 the same.

This invention relates to revolving window-sashes, and one object thereof is to provide a window frame and sash therefor which shall be capable of easy manipulation, which will 15 permit adjustment of the sash to balance the same accurately, which sash shall be held closely in contact with the stop-beads to make an approximately air-tight connection and prevent rattling, and in which the sash is supported by the sash cords or chains in such 20 manner that the strain of the sash-weights upon the sash through the medium of the sash-cords is always applied vertically, whereby 25 the sash may be positively and evenly raised and lowered.

With these and other objects in view my invention consists in the construction and arrangement of parts hereinafter set forth.

In the accompanying drawings, forming part 30 of this specification, in which like reference characters denote like parts in the several views, Figure 1 is a central sectional elevation of a window constructed according to my invention; Fig. 2, a vertical section of a portion 35 of said window-frame and a vertical elevation of a portion of said sash connected therewith and partly cut away to show the internal construction, the whole being on an enlarged scale; Fig. 3, an edge view of a portion 40 of said sash and a member thereof, being in altered position and upon an enlarged scale; Fig. 4, an edge view of a portion of said sash upon an enlarged scale; Fig. 5, a vertical section of a portion of said sash, several of the 45 parts being shown in full lines; and Fig. 6, a transverse section of the side of the sash and a supplemental member connected therewith.

In the practice of my invention I provide a window-frame 7, the vertical portions 8 of 50 which are provided with the usual stop-beads 9, and between which slidably operate the

sashes, respectively designated by the general reference characters 10 and 11, provided with window-panes 12. The construction and mounting of the sashes 10 and 11 are the same, 55 and for simplicity I will refer to but one thereof, 10, in the following description, the reference characters referring to both.

Each of the sides 12 of the sash 10 is chambered at 13, and a plate 14 is secured to the 60 side edge of the sash across the orifice of said chamber by fastening devices 15, and the central portion of said plate is struck up at 16 and provided with a longitudinal slot 17. A plate 18 fits the central portion 16 of the plate 65 14 and is shorter than the same and capable of adjustment longitudinally thereof, being connected with the slot 17 therein by bolts and nuts 19. The sash 10 is provided at each 70 side with a coextensive supplemental member consisting of a strip 20 of suitable material fitted thereto by a plurally-curved surface which matches a similar edge surface of the sash side 12, as shown at 21 in Fig. 6. The strip 20 fits between two of the stop-beads 75 9 and is transversely chambered at 22 and provided with a casing 23, which is set thereinto and secured thereto at 24. The casing 23 is annularly flanged upon its inner edge at 25, and the plate 18 is provided with an outwardly-directed collar 26, which projects into the chamber 22 and upon which the sash 10 hangs, the flanges 25 operating as bearings therefor. The sash 10 is thus free to swing upon the collars 26 at each side thereof, and 80 as the plates 18 can be adjusted relative to the plates 13 by means of the slots 17 and fastening devices 16 the sash may always be maintained in equilibrium. A stud 27 is secured in each of the collars 26, and a coiled 85 spring 28 is imposed thereon and upon the collar 26, operating within the chamber 22 and against the flange 25 and a detachable cap 28, passed upon the stud 27 and secured thereon by a pin 29. The strips 20 exactly fill the 90 spaces between the stop-beads 9, between which latter they operate, and the sash may thus entirely swing free thereof.

Above the chamber 22 the strip 20 is chambered at 30, communicating with a continuous chamber 31, extending to the adjacent end of said strip. A plate 32 is set into the 100

strip 20 directly beneath the chamber 30 and secured in place by a fastening device 33. The plate 32 is provided with a hooked upper end 34, which is directed into the chamber 30. A link member (denoted by the general index character 35) is provided with a lower transverse end 36 which fits the hooked end 34 of the plate 32 and is free to turn therein, and with parallel vertical sides 37 and a curved 5 upper transverse end 38, provided with a central slot 39. The sides 37 of the link 35 are provided with cheeks 40, in which are pivoted side bearings 41 of a pivoted plate 42, provided at its upper end with an inwardly-directed hook 43, which operates within the chamber 30 and between the sides of the link member 35.

The sash-supporting cord or chain 44 is passed through the slot 39 in the end 38 and 20 engaged with the hook 43, and the other end thereof passes upwardly, as shown in Fig. 1, and about a pulley 45, set into the side 7 of the window-frame, and thence passes downwardly in the usual chamber in the frame, 25 (not shown,) where it is connected with the sash-weight.

A screw-stud 46 is sunk into the strip 20 within the lower portion of the chamber 30, and loosely mounted thereon is a frame-shaped device 47, secured in position upon said stud by a washer 48 and nut 49, and the frame-shaped portion device 47 is provided at the upper end with heads 51, in which are journaled the end bearings 52 of a roller 53, 30 which is provided with a central peripheral beveled rim 54. The heads 51 are connected by a circular cross-head 55, which carries a central stud 56, which operates within the chamber 30 and within an opening 57 in the strip 20. A helical spring 58 is imposed upon the stud 56 and normally projects the frame-shaped device 47 or the upper end thereof, said spring bearing upon the cross-head 55 and the strip 20 adjacent the opening 57. The 35 strips 20 at either side of the sash are also chambered at 59 below the chambers 22, and the frame-shaped device 47, roller 53, rim 54, cross-head 55, stud 56, spring 58, and connected parts are duplicated in said chamber 50 59. The rims 54 of the rollers 53 bear operatively against the sides 8 of the window-frame 7 between the stop-beads 9, being pressed thereagainst by the springs 58, and thus serve as antirattlers for the sash, causing the same 55 to occupy a rigid position in the window-frame. In operating said rims form grooves in the frame sides 8, in which they operate.

The sash hangs upon the sash-chain 44, which is connected with the pivoted plate 42, 60 which is pivoted to the link member 35, which in turn is pivoted to the plate 32, and hence the sash-chains always pull vertically upon the sash, and the sashes and strip members 20 ride vertically between the stop-beads 9. 65 The sashes may also be swung in a vertical plane, as shown in Fig. 1, upon the collars 26, which bear upon the flanges 25, and by means

of the relatively-adjustable plates 14 and 18 the sashes may always be maintained upon a true pivotal center.

I have shown but one side of the sashes as provided with my improved construction; but it is understood that the latter is duplicated upon the other side and that both sashes 10 and 11 are identical in regard to the improved 75 construction described.

I do not limit myself to the specific construction and arrangement of parts herein specified, but reserve the right to vary the same within the scope of my invention.

Having fully described my invention, I claim as new and desire to secure by Letters Patent—

1. The herein-described window-sash which operates in connection with a window-frame 85 provided with stop-beads, comprising a main sash portion provided at the sides with chambers in which are sunk slotted plates; and supplemental sash members, comprising strips which fit between said stop-beads and are 90 chambered to receive bearing-casings, other plates adjustably connected with said first-named plates and provided with bearing devices which operate in connection with the bearing-casings in said supplemental strips, 95 said bearing devices being provided with spring-projected extensions which operate within said chambers in said strips, said strips being further chambered and provided therein with pivotally-mounted devices with which 100 the sash cords or chains are pivotally connected and with loosely-mounted tensional devices which bear upon the window-frame, substantially as shown and described.

2. The herein-described window-sash which 105 operates in connection with a window-frame provided with stop-beads, comprising a main sash portion provided centrally of the sides thereof with chambers, slotted plates sunk into said chambers and other plates adjustably connected therewith by means of adjusting devices which operate within said slots, said second-named plates being provided with lateral bearing devices, supplemental sash members comprising strips which operate between said stop-beads, and are chambered and provided with flanged casings within which 110 said projecting bearing devices operate, studs connected with said bearing devices and coiled springs imposed upon said studs, and bearing 115 upon said flanged casings and upon heads with which said studs are provided, substantially as shown and described.

3. In a window, a tension device which is mounted within a chamber formed in a sash member, and comprising a frame, a turnable roller carried thereby and provided with an edged periphery which is arranged to operate in connection with the window-frame, said frame being provided with a stud, a spring 125 imposed thereon, and between said frame and the window-sash, whereby said roller is normally forced into engagement with the window-frame to positively and firmly hold said 130

sash against vibration, substantially as shown and described.

4. A window-sash which operates in connection with a window-frame provided with stop-beads, said sash comprising a main sash portion provided at its sides with chambers in which are slotted plates, and supplemental sash members comprising strips which fit between said stop-beads and are chambered to receive bearing-casings, and plates adjustably connected with said first-named plates and provided with bearing devices which operate in connection with the bearing-casings in said supplemental strips, said bearing devices being provided with spring-projected extensions which operate within said chambers in said strips, substantially as shown and described.

5. A window-sash, provided at the sides

with slotted fixed plates, other plates provided with pivotal bearings and adjustably connected with said sash by means of fastening devices which operate in connection with said slotted plates and through the slots therein, and supplemental sash members comprising strips which are operatively mounted in the window-frame and provided with bearing devices in connection with which said pivotal bearings operate, substantially as shown and described.

In testimony that I claim the foregoing as my invention I have signed my name, in presence of the subscribing witnesses, this 1st day of December, 1899.

GEORGE WORTH.
